UNITED STATES PATENT OFFICE.

PHILIP BERNSTEIN, OF NEW YORK, N. Y.

DESIGN FOR A HAIR-PIN.

46,524.

Specification for Design.

Patented Oct. 13, 1914.

Application filed May 11, 1914. Serial No. 837,951. Term of patent 3½ years.

To all whom it may concern:

Be it known that I, PHILIP BERNSTEIN, a citizen of the United States, and a resident of the borough of Manhattan, city, county, and State of New York, have invented a new, original, and ornamental Design for a Hair-Pin, of which the following is a specification, reference being had to the accompanying drawings, forming part thereof.

The figure represents an elevation of a hair pin formed with a head shaped in accordance with my new design.

I claim:

The ornamental design for a hair pin, as shown.

PHILIP BERNSTEIN.
